JOSEPH M. STONE, OF NORTH ANDOVER, MASSACHUSETTS, ASSIGNOR TO
HIMSELF, GEORGE L. DAVIS, AND JOHN A. WILEY, OF SAME PLACE.

Letters Patent No. 79,872, dated July 14, 1868.

IMPROVEMENT IN CARD-CYLINDERS.

The Schedule referred to in these Letters Patent and making part of the same.

TO ALL WHOM IT MAY CONCERN:

Be it known that I, JOSEPH M. STONE, of North Andover, in the county of Essex, and State of Massachusetts, have invented a new and improved Metallic Cylinder for Carding-Machines, and a new Method of Forming the Moulds for Casting the Same; and I do hereby declare that the following is a full, clear, and exact description of the same, taken in connection with the accompanying drawings, making a part of this specification, in which—

Figure 1 represents the usual mode of constructing card-cylinders of cast iron, with the upper half in section, the lower half in elevation.

Figure 2 represents my improved cylinder, drawn in the same manner, with the method of forming the moulds for casting the same shown in blue lines; and

Figure 3 is a cross-section of the cylinder between the arms.

The subject-matter of my invention relates to the construction of metallic cylinders for carding-machines, as a substitute for the cylinders heretofore used, but more especially for the main cylinder, so called. These cylinders, as ordinarily constructed, when made of cast iron, are made up of two sections, accurately fitted and bolted together by flanges, end to end, and placed on a shaft, and then turned off true on the outside, each section having a spider or set of arms cast in it to receive the shaft, in the manner shown in fig. 1 of the drawings. But by my new mode of construction the cylinder is cast entire in one piece, with a thin shell and a series of spiders or sets of arms (three or more) cast in it, at suitable distance apart to receive the shaft, as is shown in figs. 2 and 3 of the drawings.

By this means I am enabled to construct the cylinders of less weight and much cheaper, and also prevent the tremor of either the cylinder or its shaft when in operation.

A is the cylindrical shell, and B B the spiders or sets of arms, into the central bosses of which the shaft C is fitted in the usual manner.

In fig. 2, the cylinder is represented as having four sets of arms, but for carding-cylinders of the ordinary length three sets would be sufficient.

The method in which a mould for such a cylinder is made is as follows: I prepare an iron flask, circular in form, a little longer than the extension of the cylinder, so as to have a rather thin layer of sand between it and the pattern, with a newel, cope, and as many cheeks or middle pieces as there are spaces between the spiders or sets of arms, and each cheek of a depth equal to the distance apart of the spiders. The outline of the flask and its partings are shown by the blue line in fig. 2, in which a are the newels, b b b the cheeks, and c the cope; d d d the sprues, and e e e e gatings at each set of arms.

The pattern is made of a piece of cylindrical shell, about the length of the distance between the spiders, as from f to g, a short piece of shell of a length equal to the part projecting beyond the spider, as from f to h, and a piece of shell long enough to form the other end of the cylinder, with a riser to receive the stodge, as from i to j, (part of which is to be afterward cut off,) and a pattern for the sets of arms or spiders.

The newel is first rammed up with the short piece of cylinder and the spider-pattern in the usual way and turned over. The first cheek and long piece of shell-pattern are then put on and rammed up. The cheek is then lifted off and the pattern in the newel drawn, and that part of the mould finished. The cheek is then put back and the second cheek-flask is put on. The shell-pattern is then drawn part way up, and the spider-pattern put in again and bedded at the proper place. The second cheek is then removed for part of the depth, and then the shell-pattern is drawn up till its top is even with the top of the cheek, when the ramming-up of the cheek is completed. The cheek is then lifted off and the spider-pattern drawn and the mould finished up. The cheek is then replaced, and if four sets of arms are to be made, the operation with the last cheek is to be repeated with the third cheek; but if three spiders only are to be made the spider-pattern is to be put in and the cope-

piece of the shell is to be put on, and the cope-piece of flask is to be put on and rammed up. The cope is then lifted off and patterns are to be drawn and the mould finished up and then closed.

The metal is to be run into the mould through four sprues, more or less, which I prefer to have pass through the opening between the arms, as at *d*, fig. 3, and gated into each arm, as is shown at *e*, so that the metal will flow through each spider successively as the mould fills.

By this mode of operation, by varying the depth and number of the cheeks, the cylinder can be made of the length and with the number of spiders desired.

Having thus described my invention, what I claim as new, and desire to secure by Letters Patent, is—

A card-cylinder, formed of a thin shell, with three or more spiders or sets of arms in the same, all cast in one piece, substantially as described, as a new manufacture.

Executed, March twenty-sixth, 1868.

JOSEPH M. STONE.
